UNITED STATES PATENT OFFICE.

WALTER J. MINNS, OF NEW YORK, N. Y.

COMBINED SINK, BATH, AND WASH TUB.

No. 849,254.

Specification of Letters Patent.

Patented April 2, 1907.

Application filed August 6, 1906. Serial No. 329,382.

To all whom it may concern:

Be it known that I, WALTER J. MINNS, a citizen of the United States, and a resident of the city of New York, borough of Brooklyn, in the county of Kings and State of New York, have invented a new and Improved Combined Sink, Bath, and Wash Tub, of which the following is a full, clear, and exact description.

10 The purpose of the invention is to provide a structure especially adapted for use in a small flat, tenement, or apartment house where there is little available room for necessary single plumbing and wherein in a single 15 article will be combined a sink, a bath, and a wash tub, each adaptation being as perfect and as convenient for use as a series of equivalent independent devices.

It is also a purpose of the invention to construct an article of the character described which will be not only simple, durable, and economic, but wherein the device may be readily set up, will be water-tight, and will be capable of being conveniently and expeditiously converted from one form into another for the desired use.

A further purpose of the invention is to improve upon the construction set forth in the Letters Patent granted to me September 30, 1901, No. 682,482, to the extent that the tub is rendered adaptable as a bath or a wash tub, the partition therein having a water-tight pit, and yet is capable of being swung to one side and secured, rendering the tub in 35 one compartment without interfering with the faucets, and, further, wherein the sink cannot be removed from the tub without first removing the faucets supplying it, and wherein also should any water remain in the 40 sink when it is carried up from the tub to uncover the same said water will be unfailingly directed to the tub, thus effectivelly preventing the surroundings of the tub becoming wet from such a cause.

45 The invention consists in the novel construction, and combination of the several parts, as will be hereinafter fully set forth, and pointed out in the claims.

Reference is to be had to the accompanying drawings, forming a part of this specification, in which similar characters of reference indicate corresponding parts in all the figures.

Figure 1 is a longitudinal vertical section 55 through the improved tub, the draining-board, and the sink, the two latter acting as

covers for the tub, the said view likewise showing the partition for the tub as closed in positive lines and as open in dotted lines. Fig. 2 is a vertical transverse section taken practically on the line 2 2 of Fig. 1. Fig. 3 is an enlarged sectional side elevation of the sink raised and locked in raised position and a side elevation of the splash-board for the tub and a section through a portion of the tub. Fig. 4 is a vertical section through a portion of the said sink and the splash-board, illustrating the manner in which the water is directed from said splash-board into the tub. Fig. 5 is an enlarged horizontal section through a portion of the tub at the front and the forward portion of the partition for the tub, showing said partition locked in place to divide the tub; and Fig. 6 is a horizontal section through the said partition and the rear portion of the tub.

The tub A may be made either of iron, stone, wood, or composition material and is of the type known as "wash-tubs," adapted to have two or more compartments. The tub 80 is supported by suitable legs 10. The tub A is so constructed that two compartments can be thrown into one to enable the tub to be used for bathing purposes when so desired, and to that end a flange 11 is made integral 85 with or is attached to the inner central portion of the tub, and said flange extends unbrokenly along the front, bottom, and back of the tub.

The partition A' is a movable one and is 90 adapted to fit close to the aforesaid flange 11 when in normal position transversely of the tub, as is shown in Fig. 2, and the said partition A' is provided at its back, front, and bottom edges with a grooved flange 13, facing the tub-flange 11. The said grooved flange 13 contains a rubber or other elastic packing 14, which extends some distance out beyond the left-hand side, for example, of the partition A', as is shown in Figs. 5 and 6. Hinges 100 15 connect the rear edge portion of the partition A' to the back of the tub, as is shown in Figs. 1 and 2.

At the right-hand side of the partition a latch 16 is pivoted thereto, having play in a 105 guide 17, and when the partition A' is in its normal position (shown by full lines in Figs. 1 and 2) the latch is forced down between the forward grooved flange 13 of the partition and the vertical keeper-flange 12 on the front 110 of the tub to the right of the main tub-flange 11. In this manner the packing 14 is forced

against the main tub-flange 11, providing a water-tight seal between the compartments formed by the partition.

When it is desired to use the tub as a bath-tub, the partition A' is unlocked and swung back into the right-hand end portion of the tub to an engagement with its rear wall, as is shown in Fig. 1. The upper edge of the partition A' has a longitudinal recess 20 produced therein to clear the hot and cold water faucets 18 and 19, as such faucets are provided for each compartment of the tub and are of the customary type, and the same recess forms an overflow from one tub to the other.

15 The ordinary drain-openings are provided at each side of the central flange 11 of the tub, and said drain-openings lead into twin fittings 21, connected by a pipe 22 with a waste-pipe 23 which waste-pipe extends up suitably back'd into the left-hand compartment of the tub quite close to its left-hand end, and the upper end of said waste-pipe 23 is made bell-shaped and is open.

25 A splash-board 25, preferably of metal, is secured to the wall of the room in which the tubs are erected, the said splash-board being at the rear of the left-hand compartment of the tub. The splash-board 25 is provided with a bottom 26, having transverse end flanges 27 and downwardly-extending end boards 28, which latter rest upon the upper edge of the tub, as shown in Figs. 3 and 4. The bottom 26 of the splash-board constitutes a table and is given a downward and forward inclination and extends forwardly beyond the back of the tub, as shown particularly in Fig. 4, being provided at its inner edge with a longitudinal downwardly-extending lip 30, so as to insure any water which may fall on the table 26 being directed into the tub. The lower end sections 28 of the said table are carried farther forward than is the table itself, as is shown in Figs. 3 and 4, and terminate in horizontal hooks 29, which are well over the left-hand section of the tub.

35 An apron 31 is secured to the under face of the table 26 of the splash-board 25, and said apron is carried down and engages with the inner face of the back of the tub at the top so as to unfailingly insure any drippings from the table passing down into the tub, since the water cannot find its way between the upper edge of the tub and the said table, thus preventing the floor from becoming sloppy by leakage at such point.

45 In connection with the aforesaid splash-board 25 I employ a sink C, having a horizontal marginal flange 32. When the sink is in position on the tub, the body portion extends down into the left-hand compartment of the tub, as is shown in Fig. 1, and its flanges rest on the upper left-hand end portion of the tub, and the front upper portion of said tub ex-

75 rear section of said flange 32 extends beneath the forward overhanging portion of the table-section 26 of the splash-board 25. This flange portion of the sink is provided with an upwardly-extending lip 33, which when the sink is in position for use extends up to the back of the lip 30 on the table 26 to an engagement with the said lip 30, thus providing for a water seal at this point, as is shown by dotted lines in Fig. 4.

80 At the rear end portion of the sink C outwardly-extending horizontal pins 34 are provided, which are made to enter hooks 29 on the table of the splash-board, thus constituting a hinge for the sink, enabling it to be raised and lowered, and the openings in the hooks 29 are so far to the rear that after the pins 34 have been entered into the hooks 29 the sink cannot be removed from its hinge engagement with the splash-board table until the faucets 35 which supply the sink are removed, which faucets 35 are connected with stand-pipes 36, leading to any source of supply.

85 Suitable yielding buffers 37 are provided for the forward flange portion of the sink, adapted to rest on the forward upper edge of the tub when the sink is in its normal position, and the said sink at its rear is provided in the inner face of its body with a longitudinal groove 39, adapted to contain any small amount of water that might possibly remain in the sink after it has been raised.

90 When the sink is not required, it is carried to the vertical position shown in Figs. 3 and 4 and is temporarily held in such position by a hook 38 or its equivalent fastened to the wall or to a near-by support. When the sink is in its upper or vertical position, the splash-board and the faucets in front thereof are concealed.

95 The sink is provided with the usual opening and strainer therefor for the passage of water, and said opening is surrounded by a downwardly-extending collar 40, and when the sink is in its lower or normal position (shown in Fig. 1) the said collar enters the bell-shaped upper end 24 of the waste-pipe 23.

100 A cover D is provided for the right-hand compartment of the tub; and said cover is given an inclination in direction of the sink and is hinged at its rear to a suitable support, so that it can be raised and lowered, as desired. The said cover D serves as a draining-board and is therefore provided with an upwardly-extending flange at its outer end, and its upper face is usually provided with the customary draining-grooves.

105 A tub constructed as above described meets all the requirements of families in small apartments, providing in but little space a sink, a draining-board therefor, and a tub adapted for use as wash-tubs or as a bath-tub.

110 I desire it to be understood that the pack-

ing 14 may be secured to the partition A' in any approved manner, the adaptation illustrated being only one of many that may be employed.

5 Having thus described my invention, I claim as new and desire to secure by Letters Patent—

1. The combination of a tub, a splash-board above the tub and provided with a forwardly-extending portion projecting over the side of the tub and provided at its front edge with a depending lip, a hinged sink provided at its rear edge with an upwardly-projecting rib or lip back of the depending front flange of the forwardly-projecting portion of the splash-board and guard devices extending between the tub and the splash-board in rear of said overlapping flanges, substantially as set forth.

2. In combination tubs, a tub, a sink serving as a full or partial covering therefor, a splash-board secured at the rear of the sink, and provided at its lower end with a forwardly-projecting portion extending over said tub and provided with a downwardly-extending lip at its forward longitudinal edge, said sink being provided with a marginal flange the rear section of which has an upwardly-extending longitudinal lip adapted for engagement back of the lip on the bottom of the splash-board when the sink is in horizontal position, and a hinge connection between the bottom of the splash-board and the rear section of the sink-flange, said hinge connection being in advance of the engaging lips.

3. In combination-tubs, a tub, a sink serving as a full or a partial covering therefor, a splash-board secured at the rear of the sink, the bottom of which splash-board has a forward and downward inclination and extends over said tub and is provided with a downwardly-extending lip at its forward longitudinal edge, said sink being provided with a marginal flange the rear section of which has an upwardly-extending longitudinal lip adapted for engagement back of the lip on the bottom of the splash-board when the sink is in horizontal position, a hinge connec-

tion between the bottom of the splash-board 50 and the rear section of the sink-flange, said hinge being in advance of the engaging lips and the said sink being provided with a longitudinal pocket in the inner face of the rear portion of its body, and an apron in rear of 55 said engaging lips and depending from the under face of the bottom of the splash-board along the inner face of the rear portion of the tub.

4. The combination with a tub, a splash-board fixed at the rear upper portion of the tub, having a bottom which inclines downwardly and forwardly and extends over said tub, said splash-board bottom being provided with forwardly-extending horizontal 65 hooks, faucets the supply-pipes whereof pass through the bottom of the splash-board, an apron secured to the bottom of the splash-board, extending down to an engagement with the inner upper face of the tub, a flanged 70 sink adapted to constitute a partial or a complete cover for the tub, and trunnions carried by the rear flanged section of said sink, which trunnions enter the said hooks, constituting a hinged connection between the sink and the 75 bottom of the splash-board, the entrance openings to the hooks being so far to the rear that said sink cannot be disconnected from the bottom of the splash-board while the faucets remain over the same. 80

5. The combination with a splash-board provided with forwardly-extending hooks, and faucets in front of said splash-board, of a sink having trunnions entering the said hooks and constituting a hinge connection 85 between the sink and splash-board, the entrance-openings to the hooks being so far to the rear that said sink cannot be disconnected from the bottom of the splash-board while the faucets remain over the same, substantially as set forth. 90

In testimony whereof I have signed my name to this specification in the presence of two subscribing witnesses.

WALTER J. MINNS.
